UNITED STATES PATENT OFFICE.

JOHN E. WAKEFIELD, OF WORCESTER, MASSACHUSETTS.

WRENCH.

SPECIFICATION forming part of Letters Patent No. 657,326, dated September 4, 1900.

Application filed August 3, 1897. Serial No. 646,882. (No model.)

To all whom it may concern:

Be it known that I, JOHN E. WAKEFIELD, a citizen of the United States, residing at Worcester, in the county of Worcester and State of Massachusetts, have invented a new and useful Improvement in Wrenches, of which the following is a specification, accompanied by drawings forming a part of the same, in which—

10 Figure 1 represents a side view of a wrench embodying my invention. Fig. 2 is a front or edge view of the same. Fig. 3 is a sectional view on line 3 3, Fig. 2, the upper and lower jaws of the bar being shown entire. Fig. 4 is a sectional view on line 4 4, Fig. 2. Fig. 15 5 is a perspective view of the sleeve from which the wrench-handle is formed, said sleeve being represented as it comes from the die-press.

20 Similar letters refer to similar parts in the different figures.

My present invention relates particularly to that class of wrenches known as "bicycle-wrenches;" and it has for its object to produce an improved wrench at a reduced cost and of better quality which can be conveniently carried in the pocket; and it consists in the construction and arrangement of parts, as hereinafter described, and specifically 25

30 pointed out in the annexed claims.

Referring to the drawings, A denotes the bar of the wrench, having the upper jaw A' preferably formed integrally therewith and of the same thickness as the bar A, and B 35 denotes a sliding sleeve which incloses the bar A. The sleeve B is drawn from a single piece of sheet-steel in a die-press by means of suitably-shaped dies and has its lower end B' closed, forming a pocket inclosing the end

40 of the bar A, with its upper end open to receive the bar and the lower jaw. The rear edge B² of the sleeve is straight and in contact with the rear edge A² of the bar, and the front edge B³ of the lower portion of the sleeve 45 is parallel with the rear edge B² from the lower end B' to an offset B⁵, about midway the sleeve, and the front edge B⁴ of the upper portion of the sleeve is preferably slightly flaring from the offset B⁵ to the upper end of 50 the sleeve B⁶ to afford space in front of the bar to receive the tapering body portion C of the lower jaw C' between the front edge of

the sleeve and the front edge A³ of the bar. The body C of the lower jaw is straight upon its rear edge C², which is in sliding contact with the front edge A³ of the bar. The front edge C³ of the body portion of the lower jaw is slightly tapered to correspond with the flaring front edge of the sleeve B, acting as a wedge to crowd the rear edge C² against the bar A. The body portion C of the lower jaw is attached to the sleeve B by means of rivets D D, which are provided with a small head at one end and are slightly upset at their opposite ends to firmly hold them in place and allow them to be readily removed for the purpose of detaching the lower jaw from the sleeve. The upper end of the body portion C of the lower jaw extends a short distance above the upper or open end of the sleeve B and is surmounted by the lower jaw C', said lower jaw and the body portion C being preferably of the same thickness as the bar A. The lower end of the body portion C of the lower jaw is provided with a cylindrical shank C⁴, preferably integral with the jaw and forming a shoulder C⁵, bearing against a rotating nut E, which turns upon the shank C⁴ and is provided with an exterior spiral thread E', engaging a toothed rack A⁴, 80 formed on the front edge of the bar A.

The sleeve B is notched at F just above the offset B⁵ to receive the nut E and provide a shoulder B⁷, opposing the shoulder C⁵ on the lower jaw, thereby holding the nut from longitudinal movement as it is rotated upon the shank C⁴, causing a longitudinal movement to be imparted to the bar A for the purpose of opening or closing the space between the parallel faces G G' of the upper and lower jaws. 90

The upper portion of the sleeve B constitutes a band which incloses both the bar A and the body portion C of the lower jaw, holding the rear edge C² in contact with the front edge A³ of the bar and maintaining the lower jaw in proper relation to the bar A, so that the strain upon the jaws incident to the use of the wrench will be received by the thread of the nut and the engaged teeth of the bar and that portion of the sleeve inclosing the bar and body portion of the lower jaw, thereby relieving the rivets D D, by which the lower jaw is connected to the sleeve B, the rivets simply serving to hold the lower jaw

from falling out when the wrench is not in use. By drawing the sleeve B integrally from a single piece of sheet-steel by means of suitably-shaped dies I am able not only to accurately shape the sleeve, but also to accurately determine its interior dimensions, which are governed by the size of the dies employed, and at the same time securing the flaring upper section of the sleeve with a perfectly-smooth interior surface, which incloses a chamber of accurate shape and dimensions to receive the tapering body-portion of the lower jaw.

The sleeve B is long enough to completely cover the lower end of the bar A when the faces G G' of the jaws are in contact, and the rounded closed end B' of the sleeve covers the end of the bar and prevents the access of dirt and presents a round and finished end which enables the wrench to be conveniently carried in the pocket.

By making the lower jaw separate from the sleeve B, I am able to employ soft and ductile material for the sleeve which can readily be drawn into shape by means of dies in a die-press, while the lower jaw can be hardened to secure a durable wearing-face G'.

In Fig. 5 I have shown the tubular drawn sleeve B as formed by the die-press, said sleeve forming the handle of the wrench and having its lower end B' closed, with the lower portion of the handle narrower than the upper portion, the upper and wider portion being formed by an offset B⁵ on the front edges of the handle. The narrower portion allows the handle to be conveniently grasped by the fingers and the wider portion provides a space for the insertion of the lower jaw in front of the bar. By making the tubular handle separate from the jaw I am able to draw a handle which entirely incloses the lower end of the bar from a piece of sheet-steel by means of dies instead of casting it, as heretofore done, thereby making the handle of wrought-steel instead of cast metal and much thinner and lighter than possible with cast metal and also much cheaper, the drawn handle requiring no broaching to finish the interior.

What I claim as my invention, and desire to secure by Letters Patent, is—

50. 1. The combination of a bar provided with teeth on its front edge and having an upper jaw, of a sleeve extending continuously around said bar and inclosing a space between the front edge of said sleeve and the front edge of said bar to receive the lower

jaw, a lower jaw having the body-space inclosed in said space and provided with a spindle C⁴ and a shoulder C⁵ and a rotating nut E carried on said spindle and bearing against said shoulder and engaging the teeth on said bar, and means for holding said jaw from longitudinal movement on said sleeve, substantially as described.

2. The combination with a bar and an upper jaw of a sleeve inclosing said bar having its rear edge in contact with the rear edge of said bar and having its front edge flaring to form a space in front of said bar to receive the tapering body-section of the lower jaw, a lower jaw provided with a tapering body-section fitting the flaring space in said sleeve, means for attaching said lower jaw to said sleeve and means for imparting a longitudinal movement to said bar, substantially as described.

3. In a wrench, the combination with a bar of the upper jaw, of a sleeve inclosing said bar and forming the handle of the wrench, said sleeve being drawn from a single piece of sheet metal, and having its end closed to form a closed pocket for the end of said bar, said sleeve having its upper portion engaged by an offset B⁵ in its front edge in order to provide a flaring space for a separable lower jaw and the lower jaw having a tapering top fitting said space and means for attaching said jaw to said sleeve, substantially as described.

4. In a wrench, the handle B, consisting of an integral sleeve drawn from a single piece of sheet metal and adapted to inclose the bar of the wrench, said sleeve being closed at its lower end to form a closed pocket for the end of the bar and open at its upper end to receive a separable lower jaw, said sleeve having its rear edge B² and the lower portion of its front edge B³ parallel with the edges of said bar and having an offset B⁵ in its front edge, whereby the upper portion of said sleeve is increased in width to form a flaring space for a separable lower jaw combined with the separable lower jaw provided with a tapering body adapted to fit the flaring space in said sleeve, substantially as described.

Dated this 30th day of July, 1897.

JOHN E. WAKEFIELD.
